FIG. 8

FIG. 9

UNITED STATES PATENT OFFICE

2,580,157

COMBINATION FLUID DISPENSING NOZZLE
AND FLUID LEVEL INDICATING MEANS

Joseph H. Chadwick, Portland, Oreg.

Application December 24, 1947, Serial No. 793,598

1 Claim. (Cl. 226—66)

1

This invention relates to new and novel means for indicating, by an audible signal, the fluid level in a tank or receptacle when being filled.

It is one of the principal objects of the invention to provide a device of this character particularly well adapted for use in connection with filling nozzles such as are used on gasoline metering pumps in automobile service stations, air ports, and on many other types of supply hoses fitted with a dispensing nozzle.

Another important feature of the invention is that it prevents back pressure in the tank from escaping through the filling neck or opening and carrying the contents of the tank with it, as sometimes occurs while filling automobile gasoline tanks at filling stations.

A further object is the provision of a device of this character which is readily adaptable for operative attachment to all types of filling necks or openings in fuel tanks.

A still further object resides in the simplicity and compactness of construction, and wherein its several parts are readily removable for repair or replacement and one which may be quickly and conveniently attached to the filling opening of a gasoline tank for sealing the same by simply rotating a closure cap a few turns about the nozzle to actuate means for securely gripping the walls of the filling opening.

These and other objects will appear as my invention is more fully hereinafter described in the following specification, illustrated in the accompanying drawing and finally pointed out in the appended claim.

In the drawings:

Figure 1 is a side elevation of the invention shown in operative engagement with the filling neck of a tank and with fragments broken away and partly in section for convenience of illustration.

Figure 2 is a top plan view of Figure 1.

Figure 3 is an enlarged sectional side elevation of a valve housing and cage for a float valve.

Figures 5 and 6 are enlarged sectional plan views taken along the lines 5—5 and 6—6, respectively, in Figure 4.

Figure 7 is a greatly reduced side elevation of a tank illustrating one of a number of curved filling necks in open communication with the tank.

Figure 8 is an elevation of a fuel tank with a modified form of invention applied to the filler neck thereof.

Figure 9 is an enlarged fragmentary sectional side elevation of the invention and the filler neck as shown in Figure 8.

Figure 10 is a side elevation of a conventional filling hose, actuating valve, filling nozzle.

Referring now more particularly to the drawings:

Reference numeral 1 indicates the filling neck of a tank. The upper end of the neck is turned inwardly on itself to form a locking flange 2 for engagement with a closure cap in the usual man-

2

ner. The flange is partially cut out at diametrically opposed points to form slots 3 and 4 for attaching and detaching the closure cap.

The main body of the invention consists of a 5 hollow cylindrical element, generally indicated at 5, reduced and threaded as at 6 to form a shoulder 7, and further reduced as at 8 to form a second shoulder 9. The reduced portion 8 is adapted for attachment in any approved manner with the 10 dispensing end of a supply hose and dispensing valve (not shown) such as are commonly used on gasoline pumps in automobile service stations, and the like.

The lower portion of the cylindrical element 5 15 is preferably tapered as shown, and its lower end is in open communication with a length of flexible pipe or nozzle 10 by attachment thereto in the conventional manner. The lower end of the nozzle terminates in a collar 11 formed with an 20 inlet opening 12 therein. The collar is preferably flattened over an area surrounding the inlet opening to prevent any surface-to-surface contact between the collar 11 and the inside wall of a filling neck which might tend to block off the 25 opening 12, as will be more fully hereinafter explained.

At diametrically opposed points on the periphery of the lower portion of the cylindrical member 5, I provide spring fingers 13 by means of 30 brackets 14 to which the fingers are backed by compression springs 16 to normally maintain the fingers in radially extended positions with respect to the cylindrical member. The upper end of the spring fingers should be well rounded for smooth 35 operation while moving in and out of engagement with the locking flange 2. Moreover, the flanges 14 should not extend outwardly a greater distance than the spring fingers in any position, and their upper ends should also be rounded as shown so as 40 not to interfere with disengagement from the locking flange. By means of the spring fingers engaging beneath the locking flange 2 and a locking cap 16A, the invention is held securely 45 within the filling neck 1 of the tank and the tank and neck are thereby sealed against escapement of air. The cap is threadedly mounted on the threaded portion 6 of the cylindrical element 5 and a rubber gasket 17 is carried by the cap for firm and air-tight engagement with the locking 50 flange of the filling neck.

Attached in a vertical position on the interior of the cylindrical element 5 is a valve housing 18 formed at its upper end with an opening to provide a valve seat 19 for a float valve 20 mounted 55 upon a valve stem 21 which is slidably mounted in concave ends 22 and 23 of a cage 24 securely positioned within the valve body 18. To the valve stem is secured a float 25 made of any suitable buoyant material such as cork, or the like. It 60 will be noted that the valve 20 and float 25 are spaced from the wall of the valve body 18 as best illustrated in Figures 5 and 6.

The valve housing is in open communication

3

through the valve seat 19, and an elbow fitting 26 with an air whistle 27 which for compactness encircles the reduced portion 8 of the cylindrical element 5 and is attached thereto at the shoulder portion 9 thereof.

The lower end of the valve housing 18 connects, by means of a fitting 28, with one end of a length of flexible tubing 29 whose opposite end connects with a fitting 30 on the interior of the collar 11 for open communication with the 10 inlet opening 12 formed in the collar.

The nozzle or pipe 10, and tubing 29 are flexible so as to conform, when inserted, to the curvature of filling necks of tanks, such, for instance, as illustrated in Figure 7. The open end of the 15 neck 1 is sealed by the rubber gasket and cap 16A as aforesaid, and as the filling operation begins, by the manipulation of the dispensing valve (not shown), the rising fluid level creates air pressure in the tank and the only avenue of escape for the air is through the opening 12 in the collar 11, through flexible tube 29, valve housing 18, through open valve seat 19 and into the air whistle 27 which continues to function as long as the fluid level continues to rise in the tank. 20 It will be noted that the float 25, connected with the valve 20, is of sufficient weight so as not to be lifted by the air pressure as it rests in a downward or open position with respect to the valve seat 19 as shown in Figure 4.

When the fluid in the tank reaches the level where it flows through the opening 12 into the tube 29, the air, of course, is cut off and the whistle ceases to function which indicates to the operator that the tank is filled, or that the contents of the tank has reached a level to which the end of the nozzle extends. It is to be understood that the nozzle and tube may be of any desired length for extending through filling necks of various lengths, or they may be shortened to a length whereby they may be inserted directly into the tank through an ordinary filling opening.

When the flow of the fluid into the tube 29 reaches the float 25, the valve 20 will be lifted 45 by the float to engage and close the valve seat 19 in the valve housing 18 as shown in dotted lines in Figure 4. This seals off the tube 29 and valve housing 18 to prevent escapement of the fluid through the whistle.

When the tank is filled the cap 16A is backed away from the locking flange of the filling neck and the cylindrical element 5 is rotated through 90 degrees from the position viewed in Figure 3, or through any number of degrees necessary 55 to position the spring fingers so that they are free to pass out through the slots 3 and 4 for removing the nozzle 10 from the filling neck of the tank.

In Figure 8, the filling neck is made of two 60 parts 31 and 32 joined together by a rubber collar or coupling 33, and the upper end of the part 32 is externally threaded to receive a closure cap 34 in the usual manner. Surrounding the coupling 33 is an air whistle 35 which is connected by an elbow fitting 36 with a valve housing 37 identical with that shown in Figures 1 and 4 and containing the float valve 20A adapted to be withheld from the open end of the fitting 36 while the fluid level in the tank is rising and to 70 seal off the fitting when the float is lifted by the fluid when it reaches a predetermined level in the tank.

The whistle is surrounded by a protective cov-

4

ering 38 to prevent dirt, water, and other foreign substances from entering the openings therein which would interfere with the operation of the whistle.

As previously stated, the form of the invention illustrated in Figures 1 to 6 is particularly adapted for use in connection with filling nozzles or fluid supply hoses, while the form of the invention shown in Figures 8, 9, and 10 is applied to, and made a permanent part of a filling neck of a tank. It being understood of course, that this form of the invention is applied to any type of tank, such as used on automobiles, trucks, aircraft, watercraft, fuel storage tanks, and the like.

In operating the modified form of the invention, the nozzle 39 of the supply hose shown in Figure 10 is inserted in the filling neck in the usual manner. Following this, a rubber disc or cap 40 mounted at the inner end of the nozzle is held securely against the open end of the filling neck to seal the tank against leakage of air. As in the other form of the invention, the rising fluid level in a tank being filled, forces air out of the tank which when sealed in accordance with my invention can only escape through the valve housing 37, fitting 36, and whistle 35, which continues to function to produce an audible signal so long as the fluid level in the tank is rising. Then, when the float is lifted by the fluid the valve 20A of course seals off the fitting 36 and the whistle 38 indicating to an operator that the tank is filled.

While I have shown a particular form of embodiment of my invention, I am aware that many minor changes therein will readily suggest themselves to others skilled in the art without departing from the spirit and scope of the invention. Having thus described the invention, what I claim as new and desire to protect by Letters Patent is:

An air actuated audible signal for indicating a fluid level in a tank having a filler opening, said signal consisting of an air whistle surrounding said opening and in open communication with a valve housing disposed on the interior of the opening, the valve housing being in open communication at one of its ends with the interior of the tank, a float disposed within the valve housing, a valve disposed within the valve housing and attached to said float and normally held by gravity in an open position to permit passage of air from the interior of the tank through said housing and into said whistle, said valve being adapted to be moved into a closed position to stop passage of air to the whistle when lifted by the fluid in the tank acting on the float when the fluid has reached a predetermined level therein.
